UNITED STATES PATENT OFFICE.

THOMAS T. MATHIESON, OF MADRONE, CALIFORNIA.

DESIGN FOR A COMBINED KNIFE AND FORK.

52,045.

Specification for Design.

Patented May 14, 1918.

Application filed March 22, 1918. Serial No. 224,078. Term of patent 7 years.

To all whom it may concern:

Be it known that I, THOMAS T. MATHIESON, a citizen of the United States, residing at Madrone, in the county of Santa Clara and State of California, have invented a new, original, and ornamental Design for a Combined Knife and Fork, of which the following is a specification, reference being had to the accompanying drawing, forming part thereof.

The figure is an elevation of a combined knife and fork, showing my new design.

I claim:—

The ornamental design for a combined knife and fork, as shown.

THOMAS T. MATHIESON.

Witnesses:

MARY B. PAYNE,
G. K. ESTES.
